UNITED STATES PATENT OFFICE.

EDGAR E. GREVE, OF PITTSBURGH, PENNSYLVANIA, ASSIGNEE TO OIL WELL SUPPLY COMPANY, OF PITTSBURGH, PENNSYLVANIA, A CORPORATION OF PENNSYLVANIA.

HYDRAULIC ROTARY DRILLING-MACHINE.

1,121,351.

Specification of Letters Patent. Patented Dec. 15, 1911.

Application filed March 19, 1914. Serial No. 825,874.

To all whom it may concern:

Be it known that I, EDGAR E. GREVE, a citizen of the United States residing at Pittsburgh, in the county of Allegheny and State of Pennsylvania, have invented certain new and useful Improvements in Hydraulic Rotary Drilling-Machines; and I do hereby declare the following to be a full, clear, and exact description of the invention, such as will enable others skilled in the art to which it appertains to make and use the same.

My invention relates to that class of devices employed in drilling oil or Artesian wells, commonly termed hydraulic rotary drilling machines, wherein the drill is connected with the drill-stem through the intermediary of a string of tubing, to which, as the drilling advances, sections of tubing are added from time to time until the string frequently acquires great length and weight.

Broadly considered these machines all include, in combination, a rotary table or turn-table, and means for imparting the rotation of the table to a drill-stem.

The means for imparting the rotation to the drill stem, generally stated, may be classified under two heads, viz., those adapted for use with a round drill stem, or one having a circular cross section, and those which are adapted for use with a drill-stem of non-circular cross section. Of these the former necessarily bite on the stem and are objectionable not only as tending to indent and impair the drill-stem, but also as calculated to interfere with the proper feed and jumping of the drill; therefore the latter, or those wherein the means for engaging the drill-stem conform to the configuration of and permit an unimpeded feed and jumping of the drill, are deemed preferable.

My invention relates more particularly to this latter class of rotary drilling machines, and has for its principal object the simplification and protection of the combining elements whereby effectiveness and durability of the machine is enhanced, repair facilitated, and the labor of the operator reduced.

To this end one feature of my invention embraces a rotary table formed of a plurality of superposed sections the overlying parts being provided with centrally disposed and vertically aligned openings for the

passage of a drill stem and with interlocking parts, whereby there is obtained, without loss of strength in the machine, a rotary table wherein the refitting and replacement of parts subject to the greatest wear and strain may be effected at moderate cost, and with comparatively little labor.

A second feature of my invention embraces the combination with a rotary table having suitable slide chambers, of radially disposed horizontally movable slides having drill-stem engaging surfaces adapted to coincide with a portion of the external surface of a non-circular drill-stem, and means for locking the slides in fixed relation to each other and to the drill-stem, whereby is obtained a machine which can be readily adapted to use with noncircular drill-stems of different cross sections and different cross sectional area.

A further feature of my invention embraces the combination with a rotary table of means for communicating the motion of the table to a drill-stem, and a cover for protecting said means and the rotary table from mud, &c., whereby the operator is provided with a secure footing on the rotary table, obstructions on the top of the table are eliminated, and handling of the drill-stem and strings facilitated.

There are other, minor, features of invention involving elemental construction, and particular combinations of elements, all as will hereinafter more fully appear.

In the drawings chosen for the purpose of illustrating my invention, the scope whereof will be pointed out in the claims, Figure 1 is a vertical central section of a rotary drilling machine embodying my invention, showing also, in elevation, a portion of a noncircular drill-stem adapted to be rotated by my machine. Fig. 2 is a view in elevation of a rotary table embodying my invention, the lower portion of the table being broken away. Fig. 3 is a top or plan view of the table embodying my invention, showing, in position, the slides that engage the drill stem; a noncircular drill stem in cross-section in operative position in the machine, and a portion of the cover which protects the slides from mud, &c., and facilitates handling of the drill-stem and string. Fig. 4 is a top or plan view of the upper section of a rotary table embodying my in-

vention, parts broken out to show the bottom section of the table, the cover and the slides which engage the drill-stem being removed. Fig. 5 is a vertical sectional view 5 of a table and cover embodying my invention, part of the lower section of the table broken away, taken in the plane of the line 5—5, Fig. 3, looking in the direction of the arrows. Fig. 6 is a detached plan view of 10 a roller bearing for the rotary table. Fig. 7 is a side elevation of the roller bearing shown in Fig. 6. Fig. 8 is a view in cross section of a modified form of non-circular drill-stem, and a plan view of the ends of 15 slides adapted to rotate said modified form of drill stem. Fig. 9 is a view of a lever which may be used for moving the slides into and out of engagement with the drill-stem.

20 Like symbols refer to like parts wherever they occur.

I will now proceed to describe my invention more fully so that others skilled in the art to which it appertains may apply the 25 same.

In the drawings, 1 indicates suitable skids or sills for the support of the bed-plate 2 of a rotary table 3, and also the pillow blocks 4 on which the driving shaft 5 of the table is 30 journaled.

The bed-plate 2 has the usual central or axial opening 2^a for the passage of a drill-stem, and through this opening, in this instance, there also extends a pendant annular 35 flange 3^a which forms part of the rotary table 3.

The bed-plate 2 has an annular raceway 2^b for the reception of the roller bearings of the rotary table, and in said raceway 2^b is a 40 removable race-plate 2^c over which the roller bearings travel.

The rotary table 3 is preferably comprised of two sections A and B and a cover for the upper section B, all of said members having 45 the usual axial opening for the passage of a drill-stem.

The lower section A of the rotary table is provided with an annular raceway 3^b corresponding with the raceway 2^b of the bed 50 plate 2 for the reception of the roller bearings on which the rotary table 3 travels, and in said raceway is an upper removable race-plate 3^c corresponding with the lower race-plate 2^c. These race-plates 2^c and 3^c can be 55 replaced to eliminate wear and lost motion, when required.

Section A of the table is provided with an overhang on the under surface of which is an annular rack 6 with which a pinion 7 on 60 the driving shaft 5 engages, and said section is also provided with a skirt or pendant annular flange 3^a which extends down through the central opening 2^a of bed-plate 2 to a point below the bed-plate where it is provided with a peripheral collar 8 bolted or

riveted thereto, which collar stands under the bed-plate 2, and thus prevents the rise or jumping of the rotary-table 3 under the thrust of the driving-shaft 5, or of the vibration of the drilling string.

The driving-shaft 5 is provided with the usual sprocket wheel 9 for communicating power to shaft 5, said sprocket wheel being loose on shaft 5, and it is also provided with a shifting clutch 10 splined to the shaft for coupling and uncoupling the driving shaft and sprocket wheel.

Located in the race-ways 2^b and 3^b and interposed between bed-plate 2 and rotary-table 3 are the bearing rollers on which the 8 rotary-table 3 travels.

The bearing as a whole is comprised of a series of tapering or cone-shaped rollers 11 and 12 of two different sizes or diameters having their axes in a common plane, the larger rolls 11 constituting the bearing rollers proper and the intermediate rollers 12 constituting antifriction spacing rollers, the bolts 13 and 14 constituting the axes of the rolls having their bearings in the concentric 91 rings 15 and 16.

The upper surface of the lower section A of the rotary table is provided at diametrically opposite points with upwardly projecting lugs 17 (see Figs. 3, 4 and 5), said 92 lugs being perforated for the passage of keys 18 whereby the upper section B is secured to the lower section A of the table, and it is also provided with diametrically extending channels 19 (see Figs. 2 and 4) 10 which receive ribs similarly disposed on the under surface of the upper section B of the table.

B indicates the upper section of the table which is perforated at diametrically opposite points, as at 20, for the passage of the lugs 17 on the upper surface of lower section A of the table, and it is also provided on its under surface with diametrically extending ribs 21 (see Fig. 2) which ribs, 110 when section B is in proper position on section A, enter the channels 19 in the upper surface of section A. The interlocking ribs and channels, lugs and keys above noted form an efficient connection between the sections A and B, and maintain the parts in proper and operative relation under all the strains and shocks incident to the use of the machine.

The upper surface of section B of the table has a series of converging or radially disposed vertical walls 22 connected by arc-shaped vertical walls or flanges 23 (see Figs. 4 and 5) which divide the upper surface of the top into a series of segmental recesses or 125 chambers having the outlines of truncated wedges.

The bottoms of certain of said oppositely disposed recesses or chambers 24 are slotted as at 20 for the passage of the slotted lugs or 130

projections 17 on the upper surface of lower section A of the table, while the remaining oppositely disposed recesses or chambers 25 constitute slide chambers open toward the axis of the table for the reception of the horizontally movable slides 26 which engage the drill-stem S and said chambers 25 have diametrically extending channels 27 for the reception of longitudinally disposed guide ribs 28 (see Figs. 2 and 3) on the under surface of said slides 26.

26 indicates slides having the form of truncated wedges, as have also the recesses or chambers 25 on the upper face of section B of the table, and said slides are movable therein on radial lines to and from the axis of the table. They are provided on their under surfaces with longitudinally disposed guide ribs 28 which enter the radially disposed slots 27 in the bottom of said recesses or chambers 25 to insure the proper movement of the slides in the slide chambers. In order to provide a simple and effective means for moving the slides 26 radially of the table to and from its axis of rotation I provide on the upper surface of the slide a radially disposed slot 26^a crossed by a bolt 26^b adapted to be engaged by the lower end of a lever 30 having its fulcrum on the cover of the table. The function of slides 26 is to transmit the rotary motion of the table 3 to a drill-stem of non-circular cross-section, and for this purpose the inner or axial ends of the slides 35 are given a shape to coincide with a portion of the peripheral surface of the drill-stem to be used. Means are also provided, as for instance pins 29, or their equivalents, to lock the slides 26 in position when the inner 40 ends of the slides engage the drill stem S. When in such position, owing to the wedge form of the slides and of the slide chambers, the slides will have an extended bearing on the walls of the slide chambers and a perfect 45 support on the rotary table.

In the principal figures of the drawing the inner ends of the slides have been shown as having a T-slot 26^c, the stem of the T being on a radial line of the table; because the non-circular drill-stem S chosen for purposes of illustration in the principal figures of the drawing is of circular cross-section with diametrically disposed ribs or feathers s, s, but it will be noted that in 55 the modification shown in Fig. 8 of the drawing the inner ends 26^d of the slides, which are intended to engage a drill-stem of rectangular cross-section, are of Y-shape, or are divergent, and from the foregoing 60 illustrations it will be evident that the builder of a machine can, without further invention, readily form the inner end of the slide to coincide with the cross-section of any non-circular stem he shall elect to use. 65 Slides having drill stem engaging ends of

one form can readily be substituted for those having another form of drill-stem engaging surfaces.

31 indicates the cover of the upper section 2 of the rotary table. This cover is 70 in the form of an annular plate which provides a central opening for the drill-stem, and at the same time affords ample protection to the slides 26 or drill-stem engaging devices against mud, &c., during 75 the operation of the machine, and also eliminates all projections from the top of the table, thus affording the operator a safe footing on the top of the table which facilitates the handling of the drill-stem and 80 string when required.

In cover 31 at diametrically opposite points and adapted to register with slots 26^a in the slides 26, are slots 31^a for the passage of a lever whereby the slides 26 are operated, and on opposite sides of slots 31^a are lugs 31^b through which pass bolts 31^c to form fulcrums for the lever which moves the slides. The cover 31 may be secured to the rotary table by set screws 31^d (see Figs. 2 90 and 3), or in other suitable manner. In Fig. 9 of the drawing a lever 30 adapted for this purpose is shown, and its application to the slide and cover for moving the slide is shown in dotted lines Fig. 1 of the 95 drawings.

The sections A and B comprising the rotary table are readily assembled by placing the section B on section A with the lugs 17 of section A passing through the slots 20 100 in the bottom of section B, and with the ribs 21 of section B in the channels 19 on the upper surface of section A, after which the keys 18 are passed through the slots in lugs 17, and cross pins 18^a may be passed 105 through the eyes in keys 18, if desired. The parts comprising the rotary table having been thus assembled and secured, the remaining coacting elements of the machine will be assembled, and will coact in the 110 usual manner.

Having thus described my invention, what I claim and desire to secure by Letters Patent is:

1. In a rotary drilling machine, the combination of a rotary table comprised of a plurality of superposed sections the overlying parts being provided with centrally disposed and vertically alined openings for the passage of a drill-stem, said sections having 115 interlocking parts means for connecting the several sections of the table, and means for imparting rotary motion to the table.

2. In a rotary drilling machine, the combination of a table comprised of a plurality 125 of superposed sections the overlying parts being provided with centrally disposed vertically alined openings for the passage of a drill stem and with interlocking radially disposed ribs and channels, means for detach- 130

ably connecting said sections, and means for rotating the table.

3. In a rotary drilling machine, the combination of a rotary table comprised of 5 separable sections, one of said sections having slide chambers, slides having means for engaging a non-circular drill-stem, means for securing the slides in the slide chambers, and means for rotating the table.

10 4. In a rotary drilling machine, the combination of a rotary table comprised of separable sections, one of said sections having oppositely disposed slide chambers, slides having ends adapted to engage a non- 15 circular drill-stem, means for maintaining said slides in fixed relation to each other and to the rotary table, and means for imparting a rotary movement to said table.

5. In a rotary drilling machine, the combination of a rotary table comprised of 20 separable sections, one of said sections having oppositely disposed slide chambers, slides having ends adapted to engage a non-circular drill stem, means for maintaining 25 said slides in fixed relation to each other and to the rotary table, and a cover for the slide chambers of the slide section of the rotary table.

6. In a rotary drilling machine, the combination of a rotary table, means mounted thereon for engaging a drill-stem and transmitting the movement of the table thereto, a cover for the table and for the means for

engaging the drill-stem, said cover mounted on the table and means for imparting a rotary movement to the table.

7. In a rotary drilling machine the combination of a table having superposed separable sections provided with slotted lug and key connections, means on the table for transmitting the motion of the table to a drill-stem, and means for imparting a rotary movement to the table.

8. In a rotary drilling machine, the combination of a rotary table having oppositely disposed slide chambers, said slide chambers having converging side walls, and slides having means for engaging a drill stem, said slides having the form of a truncated wedge.

9. In a rotary drilling machine, the combination of a rotary table having oppositely disposed slide chambers, said chambers having converging walls, and slides having means for engaging a drill stem, said slides having the form of a truncated wedge, said slides and slide chambers having radially disposed interlocking ribs and guide channels.

In testimony whereof I affix my signature, in the presence of two subscribing witnesses.

EDGAR E. GREVE.
